UNITED STATES PATENT OFFICE.

EARL M. SNYDER, OF DETROIT, MICHIGAN.

AMALGAM PLUGGER.

Application filed November 19, 1925. Serial No. 70,128.

This invention relates to improvements in dental instruments, particularly to instruments adapted for use as amalgam pluggers, or, for similar purposes where any plastic or semi-plastic material is to be inserted into a cavity of a tooth, the plugger having working ends in multiple or otherwise, and a concave carrying end adapted to keep the amalgam or filling material from falling off the instrument when it is in use.

The object of this invention is to produce a dental instrument as described above, which will be more efficient as a carrier of amalgam or other filling materials, in keeping such filling materials on the instrument until it is placed in the cavity of the tooth, thereby keeping such filling materials from dropping into the patient's mouth during the process of filling a tooth.

Another object of this invention is to produce a set of instruments where at least one of them can be used to fill any cavity in any tooth in the mouth efficiently with amalgam or other filling material in the easiest manner possible for the operator.

Practically all such instruments now in general use, with a few exceptions, have a serrated end only for carrying such filling materials. These ends become worn with use and become practically useless as a carrier while still working well as a plugging instrument.

Other objects will appear in the following detailed description and in the showing of the single sheet of drawings as herewith made a part of the application.

In the drawing,

Fig. 1 represents a side view of an amalgam plugger having one carrying end of concave form.

Fig. 2 illustrates a side view of an amalgam plugger in modified form over Fig. 1.

Fig. 3 represents a slight modification of Figures 1 and 2.

Figs. 4 and 5 illustrate slight modification in form of amalgam pluggers as disclosed in Figures 1, 2 and 3.

Fig. 6 represents a side view of a dental instrument slightly modified over Fig. 1.

Numeral 1 designates a gripping or

handle portion of an amalgam plugger commonly used in dentistry, having working ends 2, 3, 4, 5, 6, 7, 8, and 15.

The instruments are further supplied with carrying ends 10, 11, 12, 13, 14 and 9 and adapted to keep amalgam or other filling materials from falling off the instrument when inserting filling in the cavity of the tooth. These working ends are supplied with a concavity extending a suitable distance into the carrying ends 10, 11, 12, 13, 14, and 9, as at 16. The plugging ends of the instrument are formed with serrated surfaces at the tips and designed particularly for matrix work, as at 2 and 19.

The slight modification in form of Fig. 2 is designed for filling small and fairly large pit cavities on the buccal on molars and bicuspids.

The modified form in Fig. 5 is especially adapted for filling distal or other cavities hard to reach with other instruments on upper or lower third molars or second molars in case the third molars are not present or where any tooth is standing alone.

The modified form of instrument shown in Fig. 6 is also particularly adapted for matrix work.

The carrying end of this instrument is of concave form in all its modifications, taking more of the cone-shaped concavity, leaning slightly toward a box shape effect. This shape has been shown by experiment to be more satisfactory, both in carrying the filling material, and in allowing such filling material to completely disengage itself from the instrument upon inserting the filling material into the cavity.

This invention provides a more efficient carrying end with a better retention quality for the filling and a carrier that will completely disengage itself from such material when it is placed into the cavity of the tooth.

The dental instrument described herewith may be used for various types of plastic or semi-plastic filling material other than amalgam and will give the same advantages as described and claimed for amalgam fillings.

Numerals 17 and 18 represent sectional views of working ends 4 and 5, disclosing preferably flat working surfaces.

What I claim is:

- 5 A dental instrument having a carrying end comprising a head, the head consisting of a smooth, deep, conical shaped concavity

extending substantially the full length of the head of the instrument, for maintaining the amalgam or other plastic or semi-plastic material from falling off the instrument, whether in normal or inverted position.

In testimony whereof I affix my signature.

EARL M. SNYDER.
